UNITED STATES PATENT OFFICE

ADOLPH LEVITON AND WILLIAM KAPLAN, OF BROOKLYN, NEW YORK.

NEEDLE-OPERATING MECHANISM FOR KNITTING MACHINES.

Application filed January 21, 1925. Serial No. 3,843.

To all whom it may concern:

Be it known that we, ADOLPH LEVITON and WILLIAM KAPLAN, citizens of the United States, and residents of the city of New York, borough of Brooklyn, in the county of Kings and State of New York, United States of America, have invented a new and Improved Needle-Operating Mechanism for Knitting Machines, of which the following is a full, clear, and exact description.

This invention relates to needle operating mechanism for knitting machines.

Hitherto in carrying out knitting operations for both plain and fancy work, an extra needle bed as well as an extra set of blank needles and a set of spring jacks were employed. Such arrangement involves considerable extra expense, and has been found to be impractical for rapid operation with a view to the obtainment of a possible maximum output.

One of the objects of the present invention therefore is to reduce costs involved in incorporating certain features in a knitting machine for performing plain and fancy work, while at the same time maximizing the out-put of the machine.

Another object of the invention is to provide novel means in a knitting machine for carrying out needle operations resulting in fancy work.

Another object of the invention is to provide an arrangement of locks suitable for use in the production of fancy work, which locks, in the forward and return movements of the carriage which supports them, successively reciprocates the needles and returns their related jacks to normal positions respectively for further action thereon by the usual jacquarding mechanism.

Other objects of the invention will appear as the following specification is read in connection with the accompanying drawings, in which—

Figure 1 is a transverse sectional view on line 1—1 of Figure 2 through a portion of a knitting machine and showing the combination of elements employed in the application of the present invention.

Fig. 2 is an inside view of the reciprocating carriage and locks.

Fig. 3 is a sectional view taken on the line 3—3 of Fig. 2 looking in the direction indicated by the arrows, and showing in dot and dash lines the relative position of the needle and jack bed.

Fig. 4 is a fragmentary plan of the needle and jack bed and showing the jack controlling means.

Fig. 5 is a diagrammatic view illustrating the locks in forward travel and the different stages of needle and jack movement.

Fig. 6 is a view similar to Fig. 5, but illustrating the locks in return travel and the different stages of needle and jack movement.

Fig. 7 is a detail view showing the relative change in position of one of the locks and a portion of the needle arresting means.

Fig. 8 is a detached perspective view of a modified form of needle arrester.

Fig. 9 is a detail sectional view illustrating the application and function of the modified form of arrester shown in Fig. 8.

The present invention in its application comprises a needle bar or bed 10, needles 11 and jacks 12 movably supported in pairs respectively in grooves in the bed 10, a reciprocating carriage 13 which carries the cams commonly known in the trade as locks, and a pattern or jacquarding mechanism 14 which serves to selectively and initially lift the jacks according to the fancy pattern desired. Each of the needles 11 includes a butt 15 and a tail 16. Each of the jacks has a head 17, butt 18 and tail 19. The needles 11 are freely movable and are limited in their downward movement by a stop 20 in the nature of a wire which extends longitudinally of the bed 10. Means 21 in the nature of a convolute spring extending longitudinally of the bed 10 and attached to the bed at its opposite ends serves for frictionally controlling the jacks 12 to hold the same in different positions to which they are moved. The use of such a spring provides yieldable portions 22 in contact with each jack at opposite sides thereof. The inactive normal relationship of each pair of needles and jacks is one in which the head 17 of each jack is spaced from the tail 16 of each needle.

The mechanism 14 may be of any preferred type and serves for imparting to particular jacks 12 an initial movement to positions in the path of travel of parts of the mechanism to be described.

In order that the stitching or knitting operations of the needles resulting in fancy work may be carried out after the jacks have been selectively and initially lifted by the means 14, there is provided mechanism presently described which operates in conjunc-

tion with the butts of the jacks and needles included in the mechanism. A plate 23 is attached as at 24 to the carriage 13 and the said plate carries locks 25, 26 and 27. The locks 25 and 27 are identical and each has a cam face 28 and a cam face 29. The lock 26 is arranged between the locks 25 and 27 and has a cam face 30 which merges with the cam faces 29 of the locks 25 and 27.

10 Each of the locks 25 and 27 has a guide block 31 movable in a slot 32 in the plate 23, and a post 33 on the block 31 which extends through a slot in the supporting part 34 of the carriage and has a clamping device 35 applied thereto for effecting adjustment of the related lock. A stitch changing device 36 is adjustably carried by the part 34 and includes an assemblage of locks 37, 38, 39 and 40 which extend through an opening 41 in the plate 23 in coactive relationship with the locks 25, 26 and 27. The lock 37 has a cam face 42 which conforms to the cam face 30 of the lock 26 adjacent to which it is disposed in spaced relationship to provide a way 43. The locks 25, 26, 27 and 37 may be aptly called the needle locks. The lock 38 is arranged below the lock 37 in spaced relationship and has cam faces 44 and 45. The locks 39 and 40 are arranged between the locks 37 and 38 to be moved into and out of the space between the locks 37 and 38 according to whether plain stitching or fancy stitching is desired; the locks 39 and 40 being moved into the space when plain stitching is desired and out of the space when fancy stitching is desired. The movement of the locks 39 and 40 is accomplished by manipulating a slidale member 46 which has a cam portion 47 coacting with a cam portion 48 on a plate 49 which carries the locks 39 and 40. Pins 50 on the plate 49 are disposed respectively in openings in a wall 51 of the box 52 of device 36. The use of the pins 50 makes provision for the slidale mounting of the locks 39 and 40. The wall 51 carries posts 53 which extend through the part 34 of the carriage and each carries at its free end an adjusting device 54. A jack-return-lock 55 is yieldingly mounted on the part 34 by virtue of a post 56 and spring 57 which surrounds the post 56 and is disposed between the part 34 and the lock itself; the said lock 55 extends through the plate 23 and has a cam face 58 and a cam face 59. An adjusting device 60 is carried at the free end of the post 56. Pivotally mounted spring-actuated devices 61 are carried by the plate 23 juxtaposed respectively with respect to the needle locks.

60 Each device 61 has a cam 62 normally disposed in the way 43 in advance of the juncture between portions of the locks 25, 26, and 27 respectively.

65 Referring now to Fig. 5 of the drawings it will be seen that there has been shown a series of needles 11 and a series of jacks 12 and the said needles and jacks are shown in different positions and stages of movement in accordance with the operation of the mechanism. The jack indicated by the reference character *a* has been lifted by the means 14 so that its head 17 abuts the tail 19 of its related needle *A* and with its butt 18 in the path of the lock 38. It is to be understood that in making fancy stitches one or a plurality of jacks are lifted to present their butts 18 to the action of the lock 38. The cam face 44 in the forward movement of the carriage coactively engages the butt 18 to lift the jack or jacks to impart movement to its or their related needles, which brings the butt 15 of the needle in a position to be acted upon by the cam faces of the assemblage of needle locks. This latter action is indicated by the jacks *b* and *c* 75 needles *B*. The cam 62 of the device 61 prevents too rapid movement of the needles by virtue of the butt of the needle coming into contact therewith and causing a pivotal movement of the device 61 and allowing 80 the needle to pass smoothly along the way 43 for reciprocation of the needle. The jacks are brought down to the positions to which they have been lifted by the means 14, as indicated by the jack *d*, with its related needle *D* in contacting relationship. Upon the return movement of the carriage 13 the reciprocation of the needles is repeated. In the forward movement of the carriage the butts 18 of the initially lifted 85 jacks ride over the cam face 58 of the lock 55 which yields. Upon the return movement of the carriage the butts 18 of the jacks are acted upon by the cam face 59 of the lock 55 thus causing the jacks to move down to their normal positions respectively. The needles *D* and jacks *d* are those which are left in positions to be acted upon on the return of the carriage 13. The needles *G* and jacks *g* are those not brought 90 into play for the fancy stitching operation. The jacks *f* are those which indicate the action of the lock 55 in which it yields.

Figure 6 illustrates the different positions and movements of the needles and jacks during the return movement of the carriage 13. The action of the locks being substantially the same as when the carriage moves in a forward direction, except that the lock 55 comes into play; its cam face 59 coacting with the butts 18 of the jacks indicated at *f* to cause them to move to their original positions to be acted upon again by the means 14.

For doing plain stitching the locks 39 and 40 are moved into the space between the locks 37 and 38 which causes all of the needles to be reciprocated. When the locks 39 and 40 are moved into the space between the locks 37 and 38 each moves its adjacent 120 125 130

cam 62 to the position shown in dotted lines in Fig. 7. As stated, the action of the cams 62 is to somewhat arrest the speed of the needles to prevent them from sticking 5 or becoming lodged, and said cams also permit the needles to readily pass out of the way 43 due to the manner in which the respective devices 61 are mounted.

In Figs. 8 and 9 a modified form of the 10 device for arresting the speed of the needles is shown, and this device has a cam portion 70 which coacts with the butts of the needles; the butts riding over the cam instead of to one side as in the case of the 15 device 60.

We claim:

1. In a flat knitting machine of the character described, a set of needles, a set of jacks co-operable with the needles, a single 20 lock assembly adjustable for both plain and fancy stitching and including a needle lock having an upper section always operable on the operating needles when knitting and also having shiftable lower sections positionable to constitute a part of the needle lock 25 when plain stitching is being effected and shiftable to an inoperative position and out

of the path of the needles to provide a clearance to permit certain of the needles to idle when fancy stitching is effected, a shiftable 30 jack lock shiftable to an operative position when fancy stitching is effected and shiftable to an inoperative position when plain stitching is being effected, and a jacquard mechanism for elevating the selected jacks 35 sufficiently to permit the selected jacks to engage the jack lock when the jack lock is in an operative position.

2. In a knitting machine, a set of jacks, means for movably supporting the jacks, 40 and a coil spring having its convolutions frictionally engaged with the jacks, each jack being received between and engaged by adjacent convolutions of the coil spring.

3. In a knitting machine, a set of jacks, 45 means for movably supporting the jacks, and a coil spring having its ends fixed to said means and having its convolutions frictionally engaged with the jacks for yieldably holding the jacks in the different positions to which they are moved.

ADOLPH LEVITON.
WILLIAM KAPLAN.
